PROCESS OF AND APPARATUS FOR SEPARATING DESIRED LIQUEFIABLE CONSTITUENTS
FROM A GASEOUS MIXTURE

Application filed November 22, 1924. Serial No. 751,572.

This invention relates to processes of and apparatus for separating desired liquefiable constituents from a gaseous mixture; and in particular it relates to the production of 5 valuable normally liquid hydrocarbon mixtures of the motor fuel type, such as gasoline, from a mixture of hydrocarbon gases, such as natural gas; the procedure being characterized by compression of the hydrocarbon 10 gas mixture to assist in liquefying the constituents which it is desired to recover, and by utilizing the heat of compression to effect a refining treatment of the resultant liquid products.

15 A principal object of the invention is to provide a process and apparatus for more completely and efficiently carrying out operations of the type generally described above; and in particular for more completely and 20 efficiently recovering a stable and directly marketable gasoline from natural gas. While the invention is not limited to the treatment of natural gas for production of gasoline, that is its most useful field of application at the present time and such application will therefore be referred to more 25 particularly hereinafter in explaining the principles upon which the invention is based.

30 Briefly described, the present invention, as applied to the manufacture of gasoline from natural gas, comprises subjecting natural gas to compression in one or more stages, cooling the compressed gases to obtain a condensate, and refining this condensate by suitable heat treatment, in which the heat of the compression is utilized to eliminate from the crude condensate to the necessary extent the so-called "wild" gases; the refining 35 operation most desirably comprising a rectification of the crude condensate with the aid of a distilling column in such manner that the wild gases are eliminated either wholly or to any desired extent without substantial loss of those hydrocarbons which it is desired shall constitute the motor fuel or gasoline sought as the final product.

In order to explain further the principles 40 of the invention, one practical way in which 45 it may be carried into effect will now be de-

scribed in detail in connection with an apparatus system which is especially well suited for carrying out the process and which is itself also novel. Said apparatus system is illustrated more or less schematically in the 55 accompanying drawing which represents said system in elevation.

In practicing the novel process by means of the apparatus here illustrated, and assuming that the production of gasoline from 60 natural gas is involved, the natural gas enters the system through the pipe 10, passes through a sediment and water trap 11 and goes to the first stage compressor 12, where it is compressed to around 40 to 50 pounds, 65 for example. As a result of the work done upon the gas in this compressor, the temperature is increased to stay 200° to 250° F. The hot compressed gas leaving the first stage compressor passes through trap 13 70 where some lubricating oil collects and thence through line 14 to a still or heater indicated generally at 15. As will appear more fully hereinafter, this heater cooperates with a distilling column for rectification of the 75 crude condensate resulting from compression and cooling of the natural gas. Said heater may be of any suitable type for that purpose, but in the installation here illustrated, it is a horizontal tubular heater in which the 80 heating tubes 16, through which the hot compression gases pass, occupy only the lower half of the tube sheets, thus leaving the upper half of the vaporizing chamber as a free vapor space. This allows effective vaporization without too much entrainment of the liquid.

In passing through the heating tubes 16, some condensation of the heavier hydrocarbons occurs, such condensate passing off 85 through pipe 17, while the gases pass off through pipe 18 and enter condenser 19 of any usual or suitable type. The condensate here obtained, together with residual gas and uncondensed vapors, passes from the condenser into the trap 20, the liquid flowing off through pipe 21 which joins pipe 17, and the combined condensates then going through pipe 22 to a pump 23 which will be referred to again presently. The gas and the vapor 90

leaving trap 20 go by way of pipe 24 to the second stage compressor 25 where they are compressor to around 200 to 250 pounds. The hot compressed vapors are led through 5 lubricating oil trap 26 and pipe 27 to a second tubular still or heater 28 which may be similar to heater 15. In this heater, the compressed gases which may have attained a temperature of 200° to 250° F. in the compressor 10 give up heat to the liquid in the heater, and as a result some of the higher boiling constituents of the compressed gas are condensed and flow through pipe 29 to pump 30. The gases and uncondensed vapors leave the 15 heater through pipe 31 and pass to condenser 32. The condensate here obtained and separated from the residual gases in trap 32a goes through pipe 33 to the pump 30, the pipes 29 and 33 merging into a common pipe 34 20 entering said pump. Said residual gases leaving the condenser 32 pass through pipe 35 to a rectifying column. This column is here shown as consisting of two separate parts, a lower part 36 and an upper part 37; 25 but it is to be understood that separation of the column into distinct parts in this manner is not essential to the practice of the invention. It is however an especially advantageous arrangement and is herein preferred. 30 The entire column is heavily lagged with heat insulating material as indicated conventionally at 38. Said gas passing from the condenser through pipe 35 enters the upper rectifying column 37. Returning now to the 35 liquid condensate going to pump 23 through pipe 22, this crude first-stage compression condensate is elevated by the pump 23 through pipe 23a to a lower section of the lower rectifying column 36. The condensate impinges on 40 a spreading cone 39 and flows downwardly over the packing 40, packing of the ring type or jackstone type being especially suitable. Each of the sections containing packing as indicated may be entirely filled therewith, 45 but for simplicity of illustration the various packed sections of the complete distilling column are shown only conventionally. Instead of packed sections, the bubbler-cap and tray type of construction may be used. The crude 50 compression condensate fed to the lower section of the lower distilling column 36 is brought into intimate contact with an ascending vapor with the result that the downwardly flowing liquid becomes richer in less 55 volatile components and the ascending vapor richer in the more volatile components. In other words, the operation is a true rectification or fractional distillation. The vapor entering the bottom of the lower rectifying 60 column is the vapor coming from the heaters 15 and 28, through vapor lines 41 and 42 respectively. Liquid flows from the bottom of the lower column through pipe 43 to the heater 28, and from there through pipe 44 65 to the heater 15, from the vaporizer 15 to a

cooler 45, and from the cooler to storage tanks (not shown). The liquid product passing successively through heaters 28 and 15 may be regarded as an intermediate product whose composition approximates more and more 70 nearly, as it progresses through the heaters, the composition of the desired final liquid product. A portion of this intermediate product is vaporized in the heaters, supplying the vapor entering the lower part of the 75 column system through lines 41 and 42 above mentioned. The unvaporized portion led away from heater 15 through cooler 45 is the final product of the operation. The crude second-stage compression condensate from 80 condenser 32 and heater 28 is elevated by pump 30 through line 30a and discharged upon a distributing cone 46 in a higher section of the rectifying column system, in this instance the uppermost section of the lower 85 column 36. The liquid from the lower section of the upper column 37 also flows through a trap 47 upon this same cone. The vapor leaving the top of the lower column passes to a partial or reflux condenser 48, the condensate there formed returning through trap 49 and discharging upon aforesaid cone 46 of the lower column. The uncondensed portion of the vapor from the lower column enters the lower part of the upper column 90 through pipe 49a. The gas from second-stage condenser 32 also enters the lower part of the upper column as hereinbefore stated. 95

In the upper column the ascending gas and vapor meet descending liquid and the composition of both phases changes in the usual sense. Heptane, hexane, pentane and as much of the butane as desired may be removed from the ascending gas and vapor by contacting it with an appropriate descending liquid. 100 Gas and vapor leaving the top of the upper column through vapor line 50 pass into a condenser 51 which in most instances is cooled by artificial refrigeration and should be heavily lagged with heat insulating material. The liquid formed in this condenser consists principally of propane with some butane. This is the reflux liquid which, passing through trap 52, is discharged through pipe 53 upon 105 distributing cone 54 of the upper column and makes possible the changes in composition just mentioned. The gas, denuded of its valuable gasoline hydrocarbons, passes through a pressure relief valve 55 where the 110 pressure is lowered to any desired extent. 115

The cooling of condenser 51 may be accomplished entirely or in part by expanding the dry waste gases through a suitable engine in such manner that they are obliged to do work 120 with the result that the gas is materially cooled. The cold expanded gas may then serve as the cooling medium used in the condenser. If for any reason it is not desired to effect the cooling of condenser 51 in this 125 130

manner, it may be cooled by any of the ordinary methods of artificial refrigeration.

Ordinarily the partial condenser 48 is water cooled with very careful control so that just the required amount of reflux liquid is formed to effect the desired rectification in the lower column. The use of this partial condenser is optional, but it is especially desirable to employ, when artificial refrigeration is used to cool condenser 51, or when the condenser 51, if cooled by the expanded dry gases, would not be able to produce the full cooling effect desired. The advisability of using the partial condenser 48 thus depends somewhat upon the cost of cooling in condenser 51. As a rule it is more economical to do part of the cooling with water in the partial condenser 48 than to do all the cooling in condenser 51 if the latter has to be cooled by artificial refrigeration.

By interposing a partial condenser between the upper and lower columns, as herein disclosed, a substantial load is thus taken off the condenser 51. Were the vapor allowed to pass from the lower column directly into the base of the upper column, a thermally equivalent weight of liquid reflux would have to be formed in condenser 51. In said condenser 51, vapors and gases are mixed and it is more difficult to transfer heat from this vapor-gas mixture than if the vapors alone were present, as is substantially the case in the interposed partial condenser 48. Furthermore condensation in 51 occurs at a lower temperature. It is evident, therefore, that the use of partial condenser 48 lowers the first cost of the apparatus and reduces operating cost.

For the sake of simplicity the present schematic illustration of the apparatus omits for the most part any showing of valves in the piping connections, but it is to be understood that such valves are employed wherever it is necessary to control flow of vapor or liquid through the respective lines.

While embodiments of the novel procedure and apparatus have been hereinabove described in detail for the purpose of affording a clear understanding of the principles of the invention, it is to be understood that the invention is not restricted to the specific details mentioned.

What is claimed is:

1. The process of obtaining a valuable liquid product from gaseous mixtures containing components of such liquid product, which comprises subjecting successive quantities of such a gaseous mixture to compression in a continuous operation, thereby obtaining a hot compressed gaseous mixture and a liquid compression condensate, said compression condensate comprising components of the original gaseous mixture which are normally liquid together with undesirable volatile components, bringing said hot compressed gaseous mixture into heat-transfer-

ring relation with an intermediate liquid product more nearly approximating in composition the desired final liquid product than does the aforesaid compression condensate, whereby to volatilize a portion of said intermediate liquid product, countercurrently contacting the resultant hot vapors with the aforesaid compression condensate to reduce its content of relatively highly volatile components and to obtain said intermediate liquid product, and leading away the unvaporized portion of said intermediate product as a product of the process.

2. The process of obtaining a valuable liquid product from a gaseous mixture containing the desired components of such liquid product together with more volatile components that tend to be liquefied therewith, which comprises subjecting successive quantities of such a gaseous mixture to compression in a continuous operation, thereby obtaining a hot compressed gaseous mixture and a liquid compression condensate, said compression condensate comprising components of the original gaseous mixture which are normally liquid together with undesirably volatile components, utilizing the developed heat of compression of the gaseous mixture to vaporize a portion of an intermediate liquid product more nearly approximating in composition the desired final liquid product than does said compression condensate, countercurrently contacting the resultant hot vapors with the aforesaid compression condensate to reduce its content of relatively highly volatile components and to obtain said intermediate liquid product, and leading away the unvaporized portion of said intermediate product as a product of the process.

3. The process of producing a desired liquid hydrocarbon product from a gaseous hydrocarbon mixture containing components of such product together with undesirably volatile hydrocarbons, which comprises subjecting successive quantities of such a gaseous hydrocarbon mixture to compression in a continuous operation, thereby obtaining a hot compressed gaseous mixture and a liquid compression condensate, said compression condensate comprising normally liquid hydrocarbons together with undesirably volatile hydrocarbons, utilizing the developed heat of compression of the gaseous hydrocarbon mixture to vaporize a portion of an intermediate liquid hydrocarbon product more nearly approximating in composition the desired final liquid product than does said compression condensate, countercurrently contacting the resultant hot hydrocarbon vapors with said compression condensate to reduce its content of relatively highly volatile hydrocarbons and to obtain said intermediate liquid hydrocarbon product, and leading away the unvaporized portion of said intermediate product as a product of the process.

4. The process of producing a liquid hydrocarbon product from a gaseous mixture, containing hydrocarbons that are desired in said product and others that are more volatile but condensable therewith, which comprises compressing such gaseous mixture to obtain a crude condensate comprising the normally liquid hydrocarbons of the original gaseous mixture, likewise compressing an other quantity of said original gaseous mixture and utilizing its heat of compression to drive off undesirable volatile hydrocarbons comprising vapors from a liquid resulting from the above mentioned condensation, 15 countercurrently contacting said vapors with other quantities of liquid resulting from such abovementioned condensation before thus depriving the liquid of its undesirable volatile hydrocarbons, then subjecting this latter contacted liquid to the developed heat of compression of further quantities of such first mentioned gaseous mixture to reduce the content of undesirable volatile hydrocarbons of the liquid to produce the desired 25 liquid product.

5. The process as claimed in claim 1, further characterized by the fact that the gaseous mixture operated upon is natural gas.

6. The process as claimed in claim 3, further characterized by the fact that the gaseous mixture operated upon is natural gas.

7. The process claimed in claim 2 further characterized by the fact that the compression of said gaseous mixture is accomplished in successive stages of increasing pressure, and the resultant condensates are rectified with the aid of heat derived from the said compression stages.

8. The process of obtaining a valuable liquid product from a gaseous mixture, containing constituents ranging in boiling point from relatively high to relatively low, which comprises compressing such a gaseous mixture and thereby obtaining on the one hand a liquid consisting largely of the higher boiling constituents, and on the other hand a residual gaseous mixture consisting largely of the lower boiling constituents but including some of the higher boiling constituents, countercurrently contacting said liquid with vapors formed by bringing a liquid substantially free of said low boiling constituents into heat transferring relation with another quantity of said compressed gaseous mixture, condensing a portion of the vapors surviving such rectification at ordinary water-cooling temperatures and refluxing the condensate, and countercurrently contacting the uncondensed vapors and the aforesaid residual gas mixture with a reflux liquid obtained by condensing with the aid of refrigeration relatively low boiling constituents of said gaseous mixture, and 65 utilizing any surviving liquid from this op-

eration in the countercurrent contacting operation first mentioned.

9. The process of obtaining a valuable liquid product from a gaseous mixture containing components of widely varying volatility which comprises compressing such gaseous mixture to obtain a liquid condensate including the normally liquid components of the original gaseous mixture, rectifying said condensate with the aid of a reflux obtained at water-cooling temperatures, and subjecting the uncondensed vapors, together with the residual gases from the compression of said gaseous mixture, to rectification with the aid of a reflux obtained at a temperature below that obtainable by water cooling.

10. The process of producing natural gas gasoline which comprises compressing natural gas to obtain a condensate including the normally liquid components of the original gas, rectifying the resultant condensate with the aid of a reflux obtained at water-cooling temperatures, and rectifying the residual gases from the compression with the aid of a reflux obtained at a temperature below that obtainable by water cooling.

11. The process of producing natural gas gasoline which comprises compressing natural gas to obtain therefrom liquid condensate containing the normally liquid components of the original gas and residual gas still containing desired gasoline constituents, and separating such constituents from said residual gas by rectification, including countercurrent contacting with a liquid reflux consisting principally of hydrocarbons lower-boiling than the major portion of the natural gas gasoline to be produced, for which the necessary heat is derived from the aforesaid compression of the gas.

12. The process of producing natural gas gasoline which comprises compressing natural gas to obtain a liquid phase consisting largely of crude gasoline and a residual gaseous phase containing the less easily liquefiable constituents, rectifying the aforesaid liquid phase with the aid of the heat of compression of the gas, and recovering the desirable constituents from the residual gaseous phase by scrubbing said phase with a volatile hydrocarbon fraction previously formed from the gas itself.

13. Apparatus for producing natural gas gasoline which comprises a compressor, a heater, means for conducting hot compressed gases from said compressor into heat-transferring relation to liquid in said heater, a second-stage compressor receiving uncondensed gases from the first compressor, a second heater arranged to be heated by hot gases from the second-stage compressor, distilling column means, and means for introducing liquid condensate from both compressor's and residual uncondensed gases into the distilling column means.

14. Apparatus for producing natural gas gasoline which comprises a compressor, a heater, means for conducting hot compressed gases from said compressor into heat-transferring relation to liquid in said heater, a second-stage compressor receiving uncondensed gases from the first compressor, a second heater arranged to be heated by hot gases from the second-stage compressor, distilling column means, and means for introducing liquid condensate from both compressors and residual uncondensed gases into the distilling column means, said distilling column means including a partial condenser interposed between the locality at which the uncondensed residual gases are introduced thereinto and the locality at which said liquid condensate is introduced.

15. The process of producing natural gas gasoline which comprises compressing natural gas to obtain a condensate including the normally liquid components of the original gas, rectifying the resultant condensate with the aid of a reflux obtained at water cooling temperatures, rectifying the residual gases from the compression with the aid of a reflux obtained at a temperature below that obtainable by water cooling, and utilizing liquefiable components removed from said residual gases as a reflux in the first mentioned rectification.

In testimony whereof we hereunto affix our signatures.
